UNITED STATES PATENT OFFICE.

WILLIAM W. RANDALL, OF MARSHFIELD, ASSIGNOR TO HOWARD C. BARNES, OF BOSTON, MASSACHUSETTS.

DESIGN FOR A VIOLIN-BOX.

SPECIFICATION forming part of Design No. 14,419, dated November 13, 1883.

Application filed September 20, 1883. Term of patent 14 years.

To all whom it may concern:

Be it known that I, WILLIAM W. RANDALL, a citizen of the United States, residing at Marshfield, in the county of Plymouth and State of Massachusetts, have invented and produced a new and original Design for Violin-Boxes, of which the following is a specification, reference being had to the accompanying drawings, forming part thereof.

10 Figure 1 is a perspective view of my newly-designed violin-box, it being represented as resting upon its flat edge. Fig. 2 is a representation of the same resting upon its flat side.

15 My design consists in the shape and configuration of the base-edge A B, in connection with

that of the remaining edges of the box having the united surfaces of the parts B C, C D, D E, and E A, said surfaces having the configurations of planes and curved surfaces, as shown, one side of the box being flat, while the other 20 side, H, is made convex.

I claim—

The design for a violin-box herein shown and described, the same consisting of a flat base-edge, A B, in combination with the edges B 25 C, C D, D E, and E A.

WILLIAM W. RANDALL.
